UNITED STATES PATENT OFFICE

2,600,724

CIGARETTE EXTINGUISHER AND ASH TRAY

Michael Badner, Taylor, Pa.

Application July 22, 1949, Serial No. 106,107

1 Claim. (Cl. 131—237)

1

This invention relates to improvements in tobacco smoker's appliances and more particularly to a combination cigarette extinguisher and ashtray.

The principal object of the present invention is to provide an ashtray, having cigarette extinguishing means, which will not interfere with the use of the structure as an ashtray.

Another important object of the invention is to provide a structure which has the characteristics of being both an ashtray and a cigarette snuffer, wherein the parts coordinate in such a manner as to facilitate the extinguishing of lighted cigarettes and the collection of ashes therefrom simultaneously, the structure embodying a receptacle which primarily serves as an ashtray.

A further object of the invention is to provide a structure of the above character which is of simple construction, capable of being manufactured at a low cost and retailed accordingly, at a figure well within the means of the users of such devices.

These and various other objects and advantages of the invention will become apparent to the reader of the following description.

In the drawing:

Figure 1 is a side elevational view of the combination structure;

Figure 2 is a horizontal section taken on line 2—2 of Figure 1, looking downwardly;

Figure 3 is a vertical sectional view through the structure;

Figure 4 is a vertical sectional view partly through the structure and taken substantially on line 4—4 of Figure 1;

Figure 5 is a fragmentary side elevational and sectional view of a slightly modified form of the invention;

Figure 6 is a fragmentary horizontal sectional view taken on line 6—6 of Figure 5.

Referring to the drawing, wherein like numerals designate like parts, it can be seen that the combination structure is composed of an ashtray, generally referred to by numeral 5 and a cigarette snuffer or extinguisher, generally referred to by numeral 6.

The ashtray 5 has a bottom 7 and an inclined side wall 8, and at the center of the bottom 7 is a cylindrical riser 9, having a top or anvil 10.

The lower portion of the riser 9 is bulged out to form a shoulder 11.

The cigarette extinguisher includes an upper collar 12 and a lower collar 13, connected by a pair of connectors or posts 14, diametrically opposed, as shown in Figure 4.

2

The upper collar 12, and the post 14, define a guide for a snuffer plunger 15, this plunger 15 being of cylindrical formation and being closed at its lower end as at 16 to define a stamper, and 5 coacting with the anvil 10 to snuff out lighted cigarettes when interposed therebetween.

The upper portion of the plunger 15 is circumferentially grooved as at 17 and clinched into this is the lower edge portion of cap 18, which 10 forms an abutment for the upper end of a compression spring 19, this spring 19 extending downwardly in the plunger 15 and bearing against a cross pin 20, which has its ends located within 15 openings at diametrically opposite points in the upper collar 12, as is shown in Figure 4 and also in Figure 1.

Extending upwardly at diametrically opposite sides of the plunger 15 are slots 21 through which the end portions of the pin 20 are disposed.

20 It can now be seen that with the structure assembled in the above manner, the operation is practically patent.

When it is desired to extinguish a cigarette, the lighted end of the cigarette is set upon the 25 anvil 10 and by pushing downwardly on the cap 18, the plunger 15 is driven downwardly and the stamper 16, pressing against the lighted end of the cigarette, snuffs out the lighted end. The cigarette can then be released and will fall into the ashtray 5. The plunger 15 will be returned to its upward position by the expansion of the 30 spring 19.

A slightly modified form of the invention is shown in Figures 5 and 6. Reference character 35 5a denotes the ashtray, which has a riser 9a with an anvil top 10a.

A bridge formation 14a supports a collar 12a and a pin 20a corresponding to the pin 20, is disposed through the collar 12a, and through a 40 plunger 15a, corresponding to the plunger 15 (see Figure 3).

The plunger 15a has slots 21a therein, corresponding to the slots 21 shown in Figure 4, and through these slots are disposed the pin 20a. 45 The snuffer is constructed otherwise, strictly in accordance with the snuffer 6, shown in Figure 3, including the spring means.

Therefore, instead of having the connectors or 50 posts 14, the snuffer is supported by the bridge structure 14a, this dispensing with the lower collar 13, as shown in Figure 3.

The operation is the same as described above in connection with the first form of the invention.

55 While the foregoing description sets forth the

invention in specific terms, it is to be understood that numerous changes in the shape, size and materials may be resorted to, without departing from the spirit and scope of the invention as claimed hereinafter.

Having described the invention, what is claimed as new is:

A device of the character described comprising an ash tray having a centrally disposed integrally formed upwardly extending cylindrical riser provided with a closed top forming an anvil, an arcuate bridge diametrically affixed to the upper edge of said tray and having its central portion vertically spaced from said anvil, a hollow cylindrical guide centrally mounted in said bridge, a hollow plunger vertically slidable in said guide and having a pair of diametrically opposed vertical slots in the lower portion thereof, a transverse pin affixed in the lower portion of said guide and extending through said slots, a handle at the upper end of said plunger, and a compression spring in said plunger interposed

between the top side of said pin and the under-side of said handle.

MICHAEL BADNER.
